Specification for Design.

Patented Oct. 5, 1920.

Application filed April 28, 1920. Serial No. 377,392. Term of patent 14 years.

To all whom it may concern:

Be it known that I, JOSEPH LEDWINKA, a citizen of the United States, and a resident of Philadelphia, in the county of Philadelphia and State of Pennsylvania, have invented a new, original, and ornamental Design for a Window in the Backs of Automobile-Bodies, of which the following is a specification, reference being had to the accompanying drawing, forming part thereof.

The figure of the drawing is a rear elevation of the back of an automobile top showing the window therein of my new design.

I claim:—

The ornamental design for a window in the backs of automobile bodies.

In testimony whereof I have hereunto set my hand on this 24th day of April, A. D., 1920.

JOSEPH LEDWINKA.
